UNITED STATES PATENT OFFICE.

JOHN H. G. ZUNNER, OF ROCHESTER, NEW YORK, ASSIGNOR TO ZUNNER MACHINES COMPANY, OF ROCHESTER, NEW YORK.

KEG-WASHING MACHINE.

1,090,263.

Specification of Letters Patent. Patented Mar. 17, 1914.

Application filed December 30, 1911. Serial No. 668,795.

To all whom it may concern:

Be it known that I, JOHN H. G. ZUNNER, a citizen of the United States, and resident of Rochester, in the county of Monroe and State of New York, have invented certain new and useful Improvements in Keg-Washing Machines, of which the following is a specification.

This invention relates to a machine for washing, or otherwise treating, kegs or barrels.

Machines of the kind in question are commonly arranged to operate upon kegs which are supported by runways or seats upon which the kegs lie in horizontal position, with their bungholes at their lowermost points. The kegs are so positioned usually by means of an automatic device known as a "bung-hole-finder", which rises into engagement with the bunghole of the rotating keg and arrests it at the required position. For the purpose of washing the keg a nozzle is then introduced through the bunghole, by which the water or other fluids are discharged into the keg. In order that a number of kegs may be operated upon simultaneously, and to transfer the kegs automatically from point to point in the machine, while maintaining them in proper position for the reception of the nozzles or other instrumentalities, means have heretofore been proposed for raising each keg from its seat or support at one point of operation, moving it transversely to another point of operation, and then lowering it upon a seat or support, while maintaining the bunghole at the lowermost point.

The present invention relates particularly to mechanism for transferring the kegs in this manner.

The object of the present invention is to produce a mechanism, of the type above referred to, by which the kegs shall be raised and lowered rectilinearly, to provide more effectually against accidental rotation of the kegs from the position in which the bungholes are at the lowermost points but in which, nevertheless, the movements of the mechanism are, for the most part, through a closed curved path, so as to be produced with a minimum expenditure of power and a minimum wear upon the mechanism. To this end I employ a mechanism in which provision is made for lost motion, this lost motion being controlled by stops operable to

modify the movements of the keg-supporting device at the end-portions of the path of movement.

In the accompanying drawings: Figure 1 is a plan-view of a portion of a keg-washing machine provided with transferring-mechanism embodying the present invention; Fig. 2 is a longitudinal section of said machine; Fig. 3 is a vertical section, on the line 3—3 in Fig. 2, but on a larger scale than said figure; and Fig. 4 is an enlarged detail-view, in side-elevation, of a portion of the machine indicated by the line 4—4 in Fig. 1.

The invention is illustrated as embodied in a machine for washing the insides of kegs or barrels, this machine being provided with a bung-hole finder 99 of any ordinary or suitable form, together with a series of nozzles 111 through which water and other fluids may be discharged into the kegs through their bung-holes, in the usual manner. The bung-hole finder and the nozzles are located at regular intervals on the machine, and the present invention relates particularly to the mechanism for transferring the kegs to the bung-hole finder, and thence to the successive nozzles.

The bung-hole finder and the nozzles are mounted in a trough, of which the sides 74 are recessed to form a series of seats 95, 96, 97 and 98, upon which the kegs rest during the several operations thereon. The transferring-mechanism is provided with a series of equidistant keg-supports, in the form of recessed plates 63, fixed upon channel-bars 64 which extend horizontally on opposite sides of the trough. During the operations upon the kegs the keg-supports 63 lie entirely below the keg-seats on the trough, and move horizontally in the performance of their return-movement, which is in a direction from right to left as the machine is shown in the drawings. At the termination of this movement they arrive in the position shown in the drawings, directly beneath the keg-seats. They are then raised vertically so as to engage the bilge-portion of the kegs just outside of the keg-seats, thus raising the kegs from the seats. The keg-supports then move horizontally from left to right, thus transferring each keg from one seat to the next seat in order; and they then fall vertically so as to permit the kegs to engage and rest upon the keg-seats again.

In order to actuate the keg-supports in the

manner just described, each channel-bar 64 is provided with two studs 65, which have shanks 67 resting in horizontal slots 68 in two rack-plates 69 located near opposite ends of the channel-bar, the bars being thus supported upon the plates, and the studs have heads 66 to prevent lateral movement of the bars. The pairs of rack-plates at each end of the machine are connected by cross-bars 73, so as to provide a rigid structure, and each plate is supported by means of a guide-roller 70 journaled on the end of a gear-shaft 71. The gear-shafts are journaled, in transverse horizontal position, on columns 72 constituting portions of the frame of the machine, and each guide-roller 70 engages an endless channel in one of the rack-plates. Each of these channels has straight upper and lower horizontal portions 86, connected by semi-circular curved end-portions 87. Accordingly, the guide-rollers and the channels act to restrict the plates 69, and the parts immediately supported thereby, to movements in a closed curved path having comparatively long, horizontal, straight portions and short, curvilinear end-portions.

In order to cause the plates 69 to move in the manner referred to each gear-shaft 71 is provided, near its ends, with pinions 83 which coöperate with racks on the plates. Each of these racks is formed by a horizontal series of pins terminating, at the right-hand and left-hand ends, respectively, in pins 84 and 85 which are concentric with the semi-circular end-portions of the guide-channels. When the gear-shafts are rotated constantly in a clock-wise direction the pinions and racks operate to move the plates 69 continuously, in directions determined by the form of the guide-channels, the pinions and racks being maintained constantly in co-operative relation by the channels and the guide-rollers.

In order to rotate the gear-shafts in unison, they are provided with bevel-gears 81, meshing with bevel-pinions 80 upon a counter-shaft 79 which is journaled longitudinally on the machine. This counter-shaft, in turn, is connected, by a worm-wheel 78 and a worm 77, with a transverse power-shaft 76, which may be driven by connection with any suitable source of power.

The pinion-and-rack mechanism just described is adapted to impart vertical and horizontal movements, of the necessary amplitude and in the proper sequence, to the channel-bars and the keg-supports, but the rising and falling movements so produced, if not otherwise modified, would be curvilinear in direction, and accordingly I employ means to so modify these movements as to cause them to be rectilinear and vertical. To this end three stop-lugs 89, 90 and 91 are mounted on the outer surface of

each of the side-walls of the trough, and to coöperate with these stop-lugs each channel-bar is provided, at two points, with inwardly-projecting studs 92 upon which are mounted stop-rollers 93 and 94, respectively, 70 these studs and rollers being located, on each bar, at a distance from each other slightly greater than the space between successive keg-supports. The stop-rollers 93 and 94 coöperate with the stop-lugs 89, 90 75 and 91, all of which have vertical surfaces for this purpose, and the middle lug 89 is somewhat longer than the lugs 90 and 91, so as to project above and below the latter as shown in Fig. 4. When the plates 69, the 80 channel-bars and the keg-supports are in their lowermost position either of the rollers 93, 94 may pass beyond the lower ends of the lugs 90 and 91, respectively, and engage the lower end of the lug 89.

In Fig. 2 the mechanism is shown in the position in which it has completed its horizontal movement from right to left, and accordingly in this position, wherein the keg-supports have arrived immediately beneath 90 the keg-seats, the stop-rollers 94 have engaged the right-hand surfaces of the lugs 89. By this engagement the horizontal movement of the channel-bars is arrested. By the continued rotation of the pinions a 95 semi-circular rising-movement is next imparted to the rack-plates, while the guide-rollers 70 traverse the right-hand curved portions 87 of the guide-channels. At this time, however, owing to the sliding connections provided by the studs 65 and the slots 68, the channel-bars and the keg-supports are permitted to participate in the upward movement of the rack-plates while remaining stationary as far as horizontal movement is concerned. This upward movement is directed by the engagement of the rollers 94 with the right-hand surfaces of the lugs 89 during the first half of the semi-circular 100 movement of the rack-plates, while they are 110 still moving to the left, so that it is directly vertical. During the second half of this semi-circular movement, in which the plates move toward the right again, the guide-rollers 94 engage the inner or left-hand vertical surfaces of the lugs 91, thus continuing the rectilinear upward movement of the keg-supports until the guide-rollers 70 have come into engagement with the lower straight portions 86 of the guide-slots. 115 When this latter point in the operation is reached the stop-rollers 94 have risen clear of the upper ends of the lugs 91, thus leaving the channel-bars free to move to the right and participate in the succeeding rectilinear horizontal movement of the rack-plates, while the rollers 70 are traversing the lower straight portions 86 of the guide-channels.

An analogous operation to that just de- 130

scribed occurs at the right-hand end of the horizontal transfer-movement. At this time the step-rollers 93 engage the vertical left-hand surfaces at the upper ends of the stop-lugs 89, and then move downwardly between these lugs and the lugs 90, thus causing the keg-supports to move directly downward while the rollers 70 are in engagement with the left-hand semicircular portions 87 of the guide-channels.

The first of the keg-supports 63, located at the left-hand ends of the channel-bars 64, are adapted to raise a keg from a seat or runway (not shown) constituting either a part of the barrel-washing machine, or of any other mechanism for handling or operating upon the kegs, and to transfer the keg to the seat 95, where it may be operated upon in the usual manner by the bung-hole finder. The construction of this device is not particularly described as it may be of any ordinary or suitable form, but the drawings show rollers 103 by which the keg is supported and rotated to cause its bung-hole to be brought into engagement with the finder, and these rollers may be conveniently actuated by sprocket-chains 104, 105 and 106 connecting them with one of the gear-shafts 71, as shown in the drawings. At the next succeeding operation of the transferring-mechanism the keg in question is raised from the seats 95 and disengaged from the bung-hole finder, being then

transferred horizontally to a position directly above the seats 96, and then lowered directly upon these seats and into engagement with the first of the nozzles 111. At the next succeeding operation of the transferring-mechanism the keg is transferred, in a similar manner, to the second nozzle 111, and so on. It will be apparent that all of the instrumentalities of the machine may be operating simultaneously upon different kegs, the operation of the machine being thus continuous except for the interval occupied in transferring the series of kegs from left to right.

I claim:—

In a keg-washing machine, keg-transferring mechanism having, in combination, a keg-support, a carrier therefor, means for moving the carrier in a closed, curved path in a vertical plane, connections between the carrier and the keg-support permitting relative lost motion in a horizontal direction, and means operative, near the horizontal extremities of the path of motion of the carrier, to arrest the horizontal movement of the keg-support and restrict the keg-support at such times to rectilinear vertical movement.

JOHN H. G. ZUNNER.
